CLAIM

I claim the ornamental design for a cutter, as shown and
described in FIGS. 1-21.

DESCRIPTION

FIG. 1 is a perspective view of a cutter according to a first
embodiment, embodying a first inventive concept.

FIG. 2 is a front view of the cutter of FIG. 1.

FIG. 3 is a rear view of the cutter of FIG. 1.

FIG. 4 is a right side view of the cutter of FIG. 1.

FIG. 5 is a left side view of the cutter of FIG. 1.

FIG. 6 is a top view of the cutter of FIG. 1.

FIG. 7 is a bottom view of the cutter of FIG. 1.

FIG. 8 is a perspective view of a cutter, according to a a
second embodiment, embodying the first inventive concept.

FIG. 9 is a front view of the cutter of FIG. 8.

FIG. 10 is a rear view of the cutter of FIG. 8.

FIG. 11 is a right side view of the cutter of FIG. 8.

FIG. 12 is a left side view of the cutter of FIG. 8.

FIG. 13 is a top view of the cutter of FIG. 8.

FIG. 14 is a bottom view of the cutter of FIG. 8.

FIG. 15 is a perspective view of a cutter, according to a third
embodiment, embodying the first inventive concept.

FIG. 16 is a front view of the cutter of FIG. 15.

FIG. 17 is a rear view of the cutter of FIG. 15.

FIG. 18 is a right side view of the cutter of FIG. 15.

FIG. 19 is a left side view of the cutter of FIG. 15.

FIG. 20 is a top view of the cutter of FIG. 15; and,

FIG. 21 is a bottom view of the cutter of FIG. 15.

The dot-dashed lines shown in the drawings represent
boundary lines of the cutter and form no part of the claimed
design. The evenly spaced broken lines show portions of the
cutter that form no part of the claimed design.
